AUTOMATIC METAL-WORKING MACHINE.

1,282,496.

Specification of Letters Patent. Patented Oct. 22, 1918.

Application filed December 8, 1914. Serial No. 876,087.

To all whom it may concern:

Be it known that I, HARRY P. TOWNSEND, a citizen of the United States, residing at Hartford, in the county of Hartford and 5 State of Connecticut, have invented a new and Improved Automatic Metal-Working Machine, of which the following is a specification.

My invention relates more especially to 10 that type of metal working machines in which the articles being formed are held in a chuck, and an object of my invention, among others, is to provide such a machine with means for preventing any but perfect 15 blanks or blanks of proper size and form from being operated upon by the machine.

A satisfactory construction of machine embodying my invention and in the production and use of which the objects herein set 20 out, as well as others, may be attained, is illustrated in the accompanying drawings, in which—

Figure 1 is a view in elevation, partially in section, of a portion of a machine embodying my invention.

Fig. 2 is a top plan view of the same, with parts broken away to show construction.

Fig. 3 is a detail view illustrating the manner of delivering blanks to the carrier.

Fig. 4 is a detail view illustrating the conditions when too short a blank is delivered to the carrier.

Fig. 5 is a like view illustrating the conditions when a crooked blank is presented to the carrier.

Fig. 6 is a detail view illustrating the conditions that will exist to prevent too long a blank from being fed to the jaws, this view illustrating a portion of the carrier, feed 40 fingers and pusher.

Fig. 7 is a detail view illustrating the operation of the stop motion mechanism.

In the operation of machines of the class herein referred to, in order to produce satisfactory work much time is required to properly adjust and set the parts, this applying especially to the tools and feeding devices. Should an imperfect blank or a blank of improper size be permitted to enter the 45 chuck, the tools or other parts of the machine acting upon the blank will at once become disarranged or broken, requiring readjustment and resetting and causing much loss of time. My improved machine, herein

illustrated and described, is provided with 55 means for preventing imperfect blanks or blanks of improper size and form from getting into the chuck, or for preventing operation of the tools upon such blanks as may find their way into the chuck, the machine, 60 in either case, being promptly stopped.

In the accompanying drawings illustrating this machine the numeral 10 indicates the table thereof that may be supported in any suitable manner, 11 bearing posts rising 65 from the table, 12 bearing posts for a cam shaft located above the table, 13 a standard secured to and also rising from the table and supporting a hopper 14 at its upper end, and 15 a work spindle mounted in bearings 70 at the upper ends of the posts 11, a loose pulley 16 and a fast pulley 17 being mounted on and secured to the spindle in any desired manner. A runway 18, along which blanks slide from the hopper 14, is secured on the 75 standard, that also has bearings for a carrier shaft 19 to which a carrier 20 is secured, said shaft being rotated as by a connecting bar 21 with a crank arm 22 to place the carrier in position to receive blanks from the 80 runway, and said shaft being rotated in the opposite direction by a spring 23 to move the carrier to deliver blanks to a feeding device, one end of said spring being secured to the connecting bar 21 and its opposite end 85 to a carrier operating lever 9 that may be actuated in any suitable manner, as by a cam (not shown) on the cam shaft 24, the carrier operating mechanism above described being omitted from Fig. 2 of the drawings. 90

A pin 7 projects from the upper end of the lever 9 into a slot 8 in the connecting bar 21, so that said lever may have a movement independently of said connecting bar. The spring 23 is sufficiently strong to move 95 the connecting bar 21 and thus operate the carrier 20 under ordinary and normal conditions. When, however, an obstruction is interposed to the movement of the carrier, then the spring will yield and permit the 100 pin 7 to move along the slot 8 without effectively moving the carrier. This construction is for a purpose to be hereinafter described.

The cam shaft 24 operates a feed cam 25 105 for reciprocating a feed lever 26 mounted on a rock shaft 49 and having a supporting bar 27 upon which rotatable feed fingers 28

and a pusher 29 are mounted. Many of the parts herein illustrated and described form the subject matter of my copending application of Serial Number 847,771, filed June 27, 1914, and, except in combination with the stop motion mechanism, no claim is made herein to the elements above noted.

My invention is more especially applied to the chuck operating mechanism, and while 10 chucks of various constructions may be employed I prefer to use one in which a reciprocating member effects movement of the chuck jaws. In the special form of construction herein shown the chuck jaws 30 are 15 pivotally mounted in a chuck body 31 secured in any suitable manner to the chuck spindle 15 to be rotated thereby. The inner ends of these jaws are connected by links 32 with a chuck jaw operating plunger 33 20 mounted for reciprocating movement within the work spindle and being normally forced in a direction to close the jaws by a jaw closing spring 34, the links 32 and the plunger 33 being disposed in the form of a toggle arrangement. Chuck operating jaws 35 are 25 mounted for reciprocating movement in slots 36 in the spindle, and a chuck operating collar 37 is mounted upon said jaws for reciprocating movement therewith. The chuck 30 operating jaws are of angular form, their outer bent ends resting against the face of the collar 37 and the inner bent ends being located in recesses 38 in the plunger 33. A chuck actuating lever 39 is pivotally mounted 35 upon the frame of the machine, of which the bed constitutes a part, one end 40 of this lever being forked and each branch of the fork having rollers 41 arranged to rest against a flange on the collar 37, as shown in Fig. 1 of the drawings. The opposite end of 40 this lever is constructed to engage a chuck operating cam 42 secured to the cam shaft 24, as shown herein this end of said lever bearing a roller to engage the cam. The 45 parts are so constructed that when the plunger 33 has been forced by the spring 34 in a direction to close the chuck jaws, and the latter grasp a blank of proper size, the lever will be loose or quiescent, that is, it will have 50 no pressure against the cam 42 or against the flange on the collar 37, but will be at rest and in the position shown in Fig. 2 of the drawings so that there is no undue wear by reason of rotation of the contacting rollers, 55 such rollers being operated only at the time when the lever is moved by the cam projection on the cam 42 in a direction to open the chuck jaws. The collar 37, however, is permitted a movement in a direction to close the 60 chuck jaws to an extent more than will be required to close such jaws upon a blank of proper size, and any means may be employed, if desired, for adjusting the parts so that the machine may be adapted to work 65 upon different classes of blanks.

The cam 42 has a cam projection on its side face for forcing the lever 39 in one direction, this cam being formed to hold the chuck jaws open until after a blank has been inserted between said jaws and then release 70 the lever 39 to permit closing movement of the jaws, and a spring seated stop motion plunger 43 projects through the cam to the back face thereof, said plunger being so located that one end, in one position of the 75 plunger, may be operated upon by the lever 39 and the opposite end of the plunger, in another position thereof, will be in position to strike one end of a stop motion or releasing lever 44 mounted upon the frame of the 80 machine, the opposite end of said lever resting in position to engage a lug 45 projecting from the under side of a belt shifter 46 pivotally mounted upon the frame of the machine in position to move the belt from the 85 fast to the loose pulley and vice-versa, a belt shifter spring 47 secured to the frame of the machine and to said belt shifter operating to move the latter to force the belt from the fast pulley 17 to the loose pulley 16. 90

Whenever a blank of improper form or size reaches the lower end of the runway 18 it will result, as hereinafter described, in the actuating lever 39 assuming an abnormal position, this abnormal position being with the 95 roller on the end of the lever resting against the side of the cam 42 and hence in the path of movement of the stop motion plunger 43. This position will be caused when no object is between the chuck jaws by the action 100 of the spring 34, plunger 33 and collar 37. When the lever 39 is in this position and the stop motion plunger 43 is carried against the roller on the end of said lever by the rotating cam 42, said plunger 43 will be 105 shifted in the cam 42 so that its path of movement will be in line with the end of the stop motion lever 44, and said lever, by the operation of the plunger 43 will be rocked on its pivot and its end opposite that 110 engaged by said plunger will be moved downwardly out of engagement with the lug 45 on the belt shifter lever, and the latter will be forced by its spring 47 to shift the belt to the loose pulley and thus stop the 115 operation of the machine. This excessive or abnormal movement of the collar 37 will take place during every cycle of movement of the machine in which a defective blank, as a crooked blank, too long a blank, too 120 short a blank or too small a blank, too large a blank may be presented to the runway for delivery to the carrier. This will be effected in the following manner. The carrier being provided with blank receiving recesses in the carrier lugs 48, if too short a blank be presented the blank will assume the position shown in Fig. 4, blocking the carrier against movement. The carrier operating lever 9 will, however, be moved, the pin 125 130

7 traveling along the slot 8 and tensioning the spring 23 to permit movement of said lever as hereinbefore described, and a blank being thus prevented from delivery to the 5 feed fingers 28 and thus to the chuck jaws, the latter will close together, permitting the excessive movement of the collar 37, and effecting operation of the stop motion above described. Should a crooked blank be presented to the carrier it will assume the 10 position shown in Fig. 5, or a reverse position, the runway being of a width to compel the blank to assume one of said positions. The carrier will thus be blocked against movement and the actuation of the stop motion 15 mechanism will be effected in the same manner as above described with respect to too short a blank. Should too long a blank be presented to the carrier it will be delivered in 20 position to receive the feed fingers, but in this case the pusher 29 will strike the blank, as shown in Fig. 6 and prevent the feed fingers from grasping it, and the blank will thus not be delivered to the chuck jaws, and 25 operation of the stop motion mechanism will thus be effected as above described. Should a blank too small in diameter pass along the runway, it will be delivered by various mechanisms to the chuck jaws, but being 30 too small the chuck jaws will close to an abnormal extent and thus permit the excessive movement of the collar 37 and the actuation of the stop mechanism in the manner above described.

35 Should a blank too large in diameter pass along the runway, the blank receiving recesses in the lugs 48 will be so small that they cannot receive it, these recesses being substantially the size of the blank intended 40 to be operated upon by the machine. In this case the blank will either block the movement of the carrier or be forced back into the runway, in either instance, no blank being delivered to the feed fingers, the stop 45 motion will be caused to operate in the manner hereinbefore described.

While I have shown herein a satisfactory construction of mechanism embodying my ideas, it will be understood that this may 50 be departed from to a greater or lesser degree and yet be within the spirit and intent of the invention as defined by the claims herein.

I claim—

55 1. In a metal working machine, a chuck having chuck jaws, means for driving the chuck for operation upon a blank held therein, a chuck jaw operating member movable to an excessive degree and beyond a point 60 required to hold a blank, means for retaining the jaws in position to hold a blank, and a stop motion mechanism including a member connected with said chuck jaw operating member to be actuated thereby during 65 its excessive movement.

2. In a metal working machine, a chuck having chuck jaws, means for moving the chuck for operation upon a blank held therein, a chuck operating member movable to an excessive degree and beyond a point required to hold a blank, a cam to actuate the chuck operating member, a stop motion mechanism, and a member borne by the cam in position to be engaged and moved by the chuck operating member during its excessive movement and into position to engage and operate the stop motion mechanism. 70

3. In a metal working machine, a chuck having chuck jaws, means for driving the chuck for operation upon a blank held therein, chuck operating mechanism including a member movable to an excessive degree and beyond a point required to hold a blank, means for holding the jaws in clamping position, a cam for operating said member, a stop motion mechanism including a releasing lever, and a member borne by said cam to be engaged by said chuck operating member during its excessive movement and to 85 be moved into position to strike said releasing lever. 90

4. In a metal working machine, a chuck having chuck jaws, a chuck operating collar, connections between the jaws and collar, the latter being movable to an excessive degree beyond a point required to hold a blank, means for holding the jaws in their clamp- 95 ing position, a stop motion mechanism, and a connection between said stop motion mechanism and collar to be operated during the excessive movement of said collar. 100

5. In a metal working machine, a chuck having chuck jaws, means for moving the chuck for operation upon a blank held therein, a chuck actuating collar operatively connected with the jaws, means for holding the jaws in their clamping position, a lever co-operating with said collar, a cam to operate said lever, a member borne by the cam 105 for engagement by said lever when positioned by the excessive movement of said collar, and a stop motion mechanism including a part to be operated by said member upon the cam. 110

6. In a metal working machine, a chuck having chuck jaws, means for driving the chuck for operation upon a blank held therein, a chuck actuating collar operatively connected with the chuck jaws, means for holding the jaws in their clamping position, a lever co-operating with said collar, a cam for actuating the lever, the latter being positioned for quiescent condition during certain periods, a member borne by the cam 120 to be engaged by said lever when positioned by the excessive movement of said collar, and a stop motion mechanism including a part positioned to be engaged by the member on the cam. 125

7. In a metal working machine, a chuck having chuck jaws, means for driving the chuck for operation upon a blank held therein, a collar operatively connected with the jaws and movable to an excessive degree beyond a point required to hold a blank, means for holding the jaws in their clamping position, a cam operatively connected with said collar, a spring pressed plunger borne by said cam and normally positioned to be operated by the excessive movement of the collar, and a stop motion lever positioned to be engaged by said plunger when moved from its normal position.
8. In a metal working machine, a spindle, a chuck connected with said spindle and having chuck jaws, a belt shifter operatively positioned with respect to said spindle, means for forcing said shifter in one direction, a member borne upon the spindle operatively connected with said jaws and movable to an excessive degree beyond a point

required to hold a blank, means for holding the jaws in their clamping position, a cam 25 operatively connected with said member, a plunger borne by the cam in normal position to be operated by said member during its excessive movement, and a stop motion lever operatively connected with the belt shifter 30 and located to be engaged by said plunger in its abnormal position.

9. In a metal working machine, a chuck having chuck jaws, means for driving the chuck for operation upon a blank held therein, 35 means operatively connected with the jaws to close them, blank conveying mechanism constructed to prevent delivery of an improper blank to the chuck jaws, and a stop motion mechanism operatively connected with said jaw closing means to be operated thereby.

HARRY P. TOWNSEND.
